UNITED STATES PATENT OFFICE.

FRANK L. BUFF, OF WICHITA, KANSAS.

TRAFFIC-SIGNALING DEVICE.

1,279,648.

Specification of Letters Patent. Patented Sept. 24, 1918.

Application filed November 8, 1917. Serial No. 200,960.

To all whom it may concern:

Be it known that I, FRANK L. BUFF, a citizen of the United States, residing at Wichita, in the county of Sedgwick and State of Kansas, have invented a new and useful Traffic-Signaling Device, of which the following is a specification.

This invention relates to signaling devices particularly designed for use upon motor vehicles, one of its objects being to provide a device of this character which can be attached readily to the wind shield of an automobile and which can be adjusted readily to indicate the direction in which the vehicle is about to turn, and whether it is intended to stop or to back the machine.

A further object is to provide simple and efficient means for holding the signaling device in any position to which it may be moved.

Another object is to produce a signaling device which is cheap to manufacture, attractive in appearance, and which will be instantly recognized as a traffic signal by motorists following the machine to which it is attached.

Another object is to provide a combined signal device and mirror.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings

Figure 1 is a rear elevation of the signaling device, the same being shown by full and dotted lines in several positions that may be assumed thereby.

Fig. 2 is a plan view.

Fig. 3 is a horizontal section.

Fig. 4 is an elevation of a portion of the arm of the apparatus.

Referring to the figures by characters of reference, 1 designates an arm having a jaw 2 at one end, and adjustably secured to this arm is a clamping member 3 having a jaw 4 which co-operates with the jaw 2 to engage and clamp upon one side of a wind-shield A. Connected to the arm 1 but ad-

justable angularly thereon, is a rearwardly extending link 5 through which extends a stem 6 projecting from an arm 7 formed on the front face of a backing plate 8. The stem can be secured in any desired manner, as by means of a nut 9.

Extending through the middle portion of the plate 8 is a stem 10 projecting from the disk-like base 11 of an actuating knob 12, and mounted on this stem is a coiled spring 13 one end of which bears against the plate 8 while the other end thereof bears against a nut 14 threaded upon the stem and by means of which the tension of the spring 13 can be regulated.

Secured to the base 11 of the knob 12 is one end portion of the signal arm 15 which is preferably formed of a strip of sheet metal shaped to appear like the forearm of a person with a hand extended therefrom, as at 16. Obviously the arm 15 and hand 16 can be suitably finished with paint or the like and, as shown, a mirror 17 can be secured upon the back face of the arm 15 so that the driver can see machines approaching from the rear.

That end of the arm 15 adjacent the base 11 is concentric with the base and is lapped and retained by a finger 18 formed on the plate 8. The stem 10 is of course extended through the arm 15 and the spring 13 serves to hold the arm pressed firmly against the plate 8.

Formed in the plate or arm 15 at points 90 equidistant from the stem 10 are apertures 19 any one of which is adapted to receive the pointed end of a plunger 20 which is slidably mounted in a recess 21 formed in the arm 7 and is normally pressed outwardly 95 against the arm 15 by a spring 22 housed in the recess 21.

The finger 18 constitutes an index and is adapted to indicate any one of a series of letters printed or otherwise displayed upon the back face of the arm or plate 15 close to the rounded end thereof. In the arrangement shown the letters employed are "B," indicating an intention to move backwardly, "L," indicating an intention to turn to the left, "S," indicating an intention to stop, "R," indicating an intention to turn to the right, and "F," which is the normal position when the machine is moving forward. The positions assumed by the arm 15 and hand 16 when the different letters are indicated by the index 18 have been shown in Fig. 1

and it will be apparent that by turning the arm 15 by means of the knob 12 so as to bring it to any one of the positions stated, the driver of a machine following will be able fully to understand in what direction the machine ahead will move. The spring pressed plunger will hold the arm 15 in any position to which it may be shifted but will yield to permit adjustment of the arm whenever the knob 12 is turned.

What is claimed is:

1. A signal device including a backing plate, means for attaching it to a supporting structure, a knob revolvably connected to the backing plate, a signal arm connected to the knob and having a series of holes therein, yielding means for holding the arm pressed yieldingly against the backing plate, and a yieldable plunger normally projecting into one of the holes to maintain the signal arm in any position to which it may be adjusted.
- 15
- 20

2. A signal device including a backing plate, an index thereon, means for attaching the plate to a supporting structure, a knob revolvably connected to the backing plate, a signal arm connected to the knob and having a series of holes therein, yielding means for pressing the arm against the backing plate, a yieldable plunger carried by the backing plate and normally projecting into one of the holes to maintain the signal arm in any position to which it may be adjusted, and means on the arm and cooperating with the index to indicate the several positions of the arm.

In testimony that I claim the foregoing as my own, I have hereto affixed my signature in the presence of two witnesses.

FRANK L. BUFF.
